Primary Examiner — Prabhakar Deshmukh(74) *Attorney, Agent, or Firm* — Fay Sharpe LLP(57) **CLAIM**

The ornamental design for a combination lock system, as shown and described.

DESCRIPTION

FIG. 1 is a perspective view of a combination lock system showing my new design;

FIG. 2 is a front elevational view thereof;

FIG. 3 is a right side elevational view thereof;

FIG. 4 is a top plan view thereof;

FIG. 5 is a bottom plan view thereof; and,

FIG. 6 is a rear elevational view thereof.

The broken lines are included for the purpose of illustrating non-claimed subject matter and forms no part of the claimed design.
